UNITED STATES PATENT OFFICE

JOSEPH C. COULOMBE, OF KOKOMO, INDIANA

DESIGN FOR AN AUTOMOBILE RADIATOR SHELL

Application filed October 18, 1928. Serial No. 28,542. Term of patent 7 years.

To all whom it may concern:

Be it known that I, JOSEPH C. COULOMBE, a citizen of the United States, and a resident of Kokomo, county of Howard, State of Indiana, have invented a new, original, and ornamental Design for Automobile Radiator Shell, of which the following is a specification, reference being made to the accompanying drawing, forming a part thereof.

In the drawing, Figure 1 is a front view showing my new design, Figure 2 is a top view.

The automobile radiator shell of my design is of conventional depth.

I claim:

The ornamental design for an automobile radiator shell as shown and described.

JOSEPH C. COULOMBE.
